*Primary Examiner—Prabhakar G. Deshmukh**Attorney, Agent, or Firm—Reese Taylor***[57]****CLAIM**

The ornamental design for a container with tie tamers, as shown and described.

DESCRIPTION

FIG. 1 is a perspective view showing my new design for a container with tie tamers in the closed position;

FIG. 2 is a perspective view thereof; in an open position;

FIG. 3 is a top plan view thereof;

FIG. 4 is a side elevational view taken from the left side of

FIG. 3, the opposed side being a mirror image thereof;

FIG. 5 is an end view taken from the top of FIG. 3;

FIG. 6 is an end view taken from the bottom of FIG. 3;

FIG. 7 is a bottom plan view thereof;

FIG. 8 is a side elevational view taken from the left of FIG.

7, the opposed side being a mirror image thereof; and,

FIG. 9 is a perspective view similar to FIG. 2 showing the

invention in the open position with the tie tamers extended.
